UNITED STATES PATENT OFFICE

JAMES DOHERTY, OF CHICAGO, ILLINOIS; ELLA MAUD DOHERTY, EXECUTRIX, AND JAMES RUSSELL DOHERTY, EXECUTOR, OF SAID JAMES DOHERTY, DECEASED

SECTIONAL FURNACE

Application filed March 21, 1923, Serial No. 626,485. Renewed January 24, 1929.

My invention relates to a sectional furnace of known type, which is made up of an assembled series of hollow-water-containing sections and in which it is sought to procure a complete combustion reaction and to render the furnace smokeless by the introduction of heated auxiliary air, the structure and objects thus generally recited being familiar in this art.

10 My invention is concerned with the means for bringing about these results in the most effective manner. In the furnace in which my invention is embodied, the front sections form the fire box, the intermediate sections 15 the fire box and flue space, and the rear sections the back of the furnace and the communication between the flue space and overhead flues. The gases passing into the rear of these flues burn with a yellow flame, which 20 indicates incomplete combustion and I therefore introduce auxiliary air (preferably highly heated) into these flues near their rear ends thus changing the yellow to a blue or white flame indicating more perfect combustion. For introducing auxiliary air at this 25 point, means of simple design and low cost are employed adapted to deliver the air in a heated state into and across the fire gas flow. Such means, if the best results are to be obtained, substantially encircles the fire gas flow, and is preferably constructed as a unit which may be inserted and removed as such, and with which the structure of one or more of the hollow water-containing furnace sections 30 is adapted to coact as hereinafter explained.

Referring to the drawings:

Fig. 1 is a side elevation, partly in section of a furnace embodying my invention.

40 Fig. 2 is a front elevation on a line II—II of Fig. 1, looking toward the rear of the furnace, part of one of the air delivery boxes being in section.

Fig. 3 is a sectional plan on the lines 45 III—III of Fig. 2, and

Fig. 4 is a perspective view of the fire gas encircling air distributing box.

The furnace in which my invention is illustrated is made up of a series of hollow 50 water-containing sections 1 bolted together

in the customary way and suitably supported as by base members 2 at each side thereof and front and rear transverse plates 3 and 4 providing space beneath the sections, the forepart of which is utilized as the ash pit, an intermediate division plate 5 being employed to that end. The front plate 3 has the usual door and damper arrangements. The sections referred to are provided with aligned openings forming the fire box 6, flue space 7, overhead side return flues 8 and common escape flue 9, the flow of the gases being usual, as indicated by the arrows. Grate bars 10 of ordinary pattern support the fuel bed. The front unit 1^a is provided with a fuel feed door 11 and with clean out doors 12, whereby access to the overhead flues may be obtained.

55 In the preferred form of my invention, I make use of a flue-encircling air distributing and delivering unit, insertable and removable as such, formed as a box 13, having air delivery openings or exit means 14 around its inner walls and provided in its projecting end 15 with a damper 16 for controlling the air admission. This air delivery box is adapted to fit in a depression or countersink in a section 1^b adjacent the rear end of one of the side flues. In the specific construction illustrated, the section 1^b is provided with wall portions 17 and 18, which support the air-distributing unit 13 so that its lower side is subjected to the heat of the fire gases as appears in Figures 1 and 2. The back wall of the recess of the section 1^b is marked 19 and the adjacent side wall of the recess is marked 20. The rear side of the air-box 13 rests against the wall 19 and its upper side against the angular wall 20. A similar air box is similarly arranged in each side flue, the design of the section 1^b being symmetrical and thus the wall portions 18, which support the inner ends of the boxes, are formed by the ends of the middle cross wall member 21 of said section. As thus arranged the inner ends of the boxes may be directly exposed to the fire gas flow in the middle flue so that the air drawn into the boxes is thoroughly heated prior to its delivery through the exit means 14.

60 It will be evident that the depression or 100

recess receiving the air distributing and delivery box might be formed in faces of adjacent sections instead of entirely in the face of one section but the construction shown being cheapest and simplest is preferred. 5 The terms "front face" and "front wall" as used in several of the claims apply to either transverse face of the section. It will be observed that the air delivering inner walls of the box 13 are shown in registry with and as, 10 in effect, constituting a part of the inner flue walls. This is desirable since the box thus does not restrict the flue passage. It will be observed further that box-receiving recesses 15 in the section 1^b are open on their outer sides so that if necessary the boxes can be inserted after assembly of the sections, a luting of stove putty being used to seal the crevice around it; obviously the boxes when so mounted are readily removable, which is desirable. 20

While thorough distribution and advance heating of the air promotes the combustion reaction generally throughout the firegas flow in the flue, it is nevertheless advantageous and a part of this invention to introduce air into the side flues at about the point stated, even where such distribution or prior heating is not effected, and the modification 25 illustrated in Figs. 5 and 6 shows a construction in which this object is obtained, simply by the provision of sleeves or bushings 22 inserted in openings 23 through the water space at the outer sides of the respective side flues 8, and preferably located in recesses 23 30 open to the front for convenience in casting and ready assembling. Butterfly or other dampers 24 control the admission of air.

The term "fire gas flow space" as used in 40 some of the claims is intended to imply limiting or defining structure and is to be understood as applicable to the fire box as well as to flues and passages through which fire gases may flow. The phrase "laterally adjoining" 45 also made use of in certain claims is designed to state the relation of flues 8 and 9 to the fire box as well as the relation of flues 8 and 9 to each other.

Claims:

50 1. A sectional furnace made up of an assembled series of cast hollow water-containing sections having in their lower part aligned openings forming a firebox and flue space in rear thereof and in communication therewith and having in their upper part aligned openings constituting an overhead return flue in communication with said flue space and firebox, and fire-gas-embracing air delivery means having its inner walls in substantial 55 registry with said return flue so as to form in effect a part of said flue for distributing air and delivering it to the fire gas flow in the flue. 60

2. A sectional furnace made up of an assembled series of cast hollow water-contain-

ing sections having in their lower part aligned openings forming a firebox and flue space in rear thereof and in communication therewith and having in their upper part three transversely related series of aligned openings forming overhead return flues at each side of the furnace and an intermediate escape flue receiving gases from the return flues which are in communication with the flue space; and a removable metal air distributing fire-gas-flow-embracing box located in each of said overhead return flues near the rear or entering end thereof and constituting in effect a part of the flue walls. 70 75

3. A sectional furnace made up of an assembled series of cast hollow water-containing sections having in their lower parts aligned openings forming a firebox and flue space in rear thereof and in communication therewith and having in their upper part aligned openings constituting an overhead return flue, one of said sections adjacent the rear of said overhead flue having in its front face a depression bordering on said overhead flue, and an auxiliary air delivery unit, embracing the fire gas flow in the flue, fitting in said depression or recess so as to take up substantially the space between the said section and the section immediately adjacent the same at the point where said recess is located and constituting in effect a part of the flue. 80 85 90

4. A sectional furnace made up of an assembled series of cast hollow water-containing sections having in their lower part aligned openings over the same constituting a flue in communication therewith, said hollow water-cooled structure having therein air-box-receiving space bordering on said flue, and an air delivery box removably seated in said space constituting part of the flue wall, embracing the flue space and abutting on the fire gas flow in said flue and delivering air thereto. 100

5. A sectional furnace made up of an assembled series of cast hollow water-containing sections having in their lower part aligned openings forming a firebox and flue space in rear thereof and in communication therewith and having in the upper part aligned openings constituting an overhead return flue, said hollow water-containing structure having air-box-receiving space surrounding said return flue and opening through an outer wall of the furnace, and an air delivery box insertable into and removable from said space through said wall as a unit and when seated therein embracing the flue space and abutting on the fire-gas flow in said flue. 110 115 120 125

6. A sectional furnace made up of an assembled series of cast hollow water-containing sections, having in their lower part aligned openings forming a firebox and flue space in rear thereof and in communication 130

therewith and having in their upper part sets of aligned openings constituting overhead return flues extending lengthwise, one at each side of the furnace, and in communication with the flue space and the firebox, and an intermediate flue to which the return flues deliver, there being also an opening to each of said overhead flues from the combustion space below it, and side openings from each return flue to the intermediate flue, and air delivery devices each respectively closing the said two openings to and from its return flue.

7. A sectional furnace made up of an assembled series of cast hollow water-containing sections having in their lower part aligned openings forming a firebox and flue space in rear thereof and in communication therewith, and having in their upper part aligned openings constituting overhead side flues in communication with said flue space and firebox, and fire-gas-embracing air delivery means located adjacent the rear end of each of said overhead side flues and conforming to the inner walls of the side flues and leaving the flue space substantially unobstructed.

8. A sectional furnace made up of an assembled series of cast hollow water-containing sections having in their lower part aligned openings constituting a fire box and aligned openings over the same at each side of the furnace constituting overhead return flues in communication with said fire-box, and a fire gas embracing air delivery box bordering on and delivering air to each side flue space, closing an opening from the flue to the fire gas space below it and whose imperforate underside is subject to contact by fire gases passing from the fire box to the flue.

9. A sectional furnace made up of an assembled series of cast hollow water-containing sections having in their lower part aligned openings constituting a fire box and flue space in rear thereof and in communication therewith, and three series of aligned openings arranged in transverse relation above the fire box openings, and an air delivery box embracing and delivering to the fire gas flow space of each side flue and closing an opening to the intermediate flue, said boxes thus having their mutually adjacent sides subject to contact by fire-gases in the intermediate flue, openings being provided for permitting fire gases to pass from the fire box to the overhead flues.

10. In a sectional furnace a hollow water-containing section having an opening in its lower part constituting combustion or flue space and three transversely related flue openings above the same, the said section having a depression in its front wall adjacent each of said side return flue openings extending to the middle flue opening and adapted to receive a flue-opening-embracing air delivery

unit, whereby each air delivery unit is adapted to be subject to contact of fire gases in its side flue opening and in the middle flue opening.

11. In a sectional furnace a hollow water-containing section having an opening in its lower part, constituting combustion or flue space and three transversely related flue openings above the same, the said section having a depression in its front fall adjacent each of said side return flue openings extending to the middle flue opening and adapted to receive a flue space-embracing air delivery unit, the said section having part of its front wall displaced rearwardly and extending from each side flue space to the combustion or flue space, whereby each air delivery unit is adapted to be subject to contact of fire gases in its side flue opening and in the middle flue opening and to contact of fire gases passing from the fire box to the flue space above it.

12. A sectional furnace made up of an assembled series of cast hollow-water-containing sections having in their lower parts aligned openings forming a firebox and flue space in rear thereof and in communication therewith and having in their upper part aligned openings constituting an overhead flue in communication with the flue space and firebox, there being also an opening to said overhead flue from the combustion space below it, and a separately made air delivery device constructed to close said opening when placed therein and to be contacted by fire gases passing from the firebox to said flue and having means to deliver air to said overhead flue.

13. In a sectional furnace, an assembled series of hollow water-containing sections forming by openings in the structure of successive sections laterally adjoining fire gas flow and return flow spaces, there being intermediate the lengths of said fire gas flow spaces an opening between water cooled walls from one of said fire gas flow spaces to the other, and a separately made metal air delivery device supported in and obstructing said opening by imperforate wall structure facing one of said fire gas flow spaces and having wall structure facing the other and provided with means for delivering thereto air thus heated.

14. In a sectional furnace, assembled hollow water-containing sections forming by openings therein three adjoining fire gas flow spaces having water cooled walls, one of said fire gas flow spaces opening into each of the other two intermediate their lengths, said openings having water cooled walls, and a separately made hollow air delivery device occupying both said openings, subject to fire gas contact in each of said two fire gas flow spaces, and having means for delivering air thus heated to the other of said fire gas flow spaces.

15. In a sectional furnace, an assembled series of transverse hollow water-containing sections having sets of communicating openings having defining water cooled walls and forming four adjacent fire gas flow spaces, there being openings having water cooled walls and extending from each of said fire gas flow spaces into two of the others, and separately made air delivery conduit means 50 removably supported in said structure in position to occupy all said inter-flue openings, said conduit means being provided with means for delivering to two of said fire gas flow spaces air heated by contact with said conduit means of fire gases in two of said other fire gas flow spaces.
16. In a sectional furnace, an assembled series of hollow water-containing sections forming by openings in the structure of successive sections substantially parallel fire gas flow spaces having defining water cooled walls, the sectional structure providing an opening from one to the other between water cooled walls and a correspondingly located opening from the outside of the furnace to one of said defined fire gas flow spaces, and a separately made air delivery device of a size and shape enabling it to be inserted and removed through said last opening and occupying the opening between said fire gas flow spaces, said air delivery device having opposite sides respectively perforate and imperforate each facing one of said respective fire gas flow spaces to distribute to one fire gas flow space air heated by fire gases in the other. 95
17. In a sectional furnace, a hollow water-containing section having an opening in its lower part providing defined space for combustion and three flue openings above the same extending through the section from front to rear and substantially aligned horizontally, the said section having depressions in its front wall extending from the outside of the section to each side flue opening and from each side flue opening to the flue opening between them and providing a recess with water-cooled walls adjacent each side flue adapted to receive an air delivery unit. 100
18. In a sectional furnace, an assembled series of hollow water-containing sections having sets of communicating openings having water cooled walls and forming four laterally adjoining fire gas flow spaces, there being intermediate the ends of each of said spaces openings into each of two of the others, the walls defining said openings being water cooled, and two separately made air delivery conduits of such size and shape as to occupy all said openings, each subject to contact of fire gases in two of said fire gas flow spaces and provided with means for delivering to another of said fire gas flow spaces air heated by such contact. 115
19. A sectional furnace comprising an assembled series of cast hollow water-containing sections and having a fire-box and a flue above and in communication therewith having water-cooled walls, said hollow water-containing sectional structure having a recess extending along a side of said flue and to its flue space and an opening from the outside of the furnace to the recess and flue space, a separately made removable air duct fitting said recess and removable therefrom through said opening without disassembling the sections, said air duct having inlet means for outside air and internal outlets for distributing air to the fire-gas flow in the flue. 120
- In testimony whereof, I have signed this 80 specification.
- JAMES DOHERTY.
